(57) **CLAIM**

The ornamental design for a collapsible feeding bottle for an infant, as shown and described.

DESCRIPTION

FIG. 1 is a front elevation view of a collapsible feeding bottle for an infant showing our design.

FIG. 2 is a top plan view thereof;

FIG. 3 is a back elevation view thereof;

FIG. 4 is a perspective view thereof;

FIG. 5 is a bottom view thereof;

FIG. 6 is a side view thereof, an opposite side view being a mirror image thereof;

FIG. 7 is an exploded perspective view thereof, showing a full extension;

FIG. 8 is a front elevation view thereof, showing an extension; and,

FIG. 9 is another front elevation view thereof, showing a further extension.
